UNITED STATES PATENT OFFICE.

MATEUSZ SPIRIKOWICZ, OF CICERO, ILLINOIS.

LOCK.

1,032,631.

Specification of Letters Patent. Patented July 16, 1912.

Application filed December 23, 1911. Serial No. 667,551.

To all whom it may concern:

Be it known that I, MATEUSZ SPIRIKOWICZ, a subject of the Czar of Russia, residing at Cicero, in the county of Cook and State of Illinois, have invented certain new and useful Improvements in Locks, of which the following is a specification.

This invention relates to certain new and useful improvements in a combination lock 10 for doors, and it consists in certain peculiarities of the construction, novel arrangement, and operation of the various parts thereof, as will be hereinafter more fully set forth and specifically claimed.

15 The principal object of the invention, is to provide a lock which shall be simple and inexpensive in construction, strong, durable, and efficient in operation, and which shall be so made, that a great number of combinations may be formed, and the same easily changed.

Another object of the invention is to so construct and arrange the door and lock with respect to one another, that the lock 25 will be protected from rain and snow, and also they will be shielded from interference or manipulation by children or mischievous persons.

Other objects and advantages of the invention will be disclosed in the subjoined description and explanation.

In order to enable others skilled in the art to which the invention pertains, to make and use the same, I will now proceed to describe it referring to the accompanying drawing in which—

Figure 1, is a view in side elevation of a portion of a door with a lock embodying the invention in place thereon, said view showing a portion of one of the protecting slides for the lock broken away in order to illustrate the indicating or combination rings of the lock. Fig. 2, is a vertical sectional view taken on line 2—2, of Fig. 3. Fig. 3, 40 is a side view partly in section and partly in elevation of a portion of the door showing the lock and its frame located in a suitable mortise therein, and illustrating the locking bolt projected. Fig. 4, is a face view of one of the disks of one of the indicating or combination rings of the lock, and Fig. 5, is an inner view of the other disk of one of said rings.

Like numerals of reference refer to corresponding parts throughout the different views of the drawing.

The reference numeral 10, designates a portion of a door which may be of the ordinary or any preferred construction, but has at one of its edges and at a suitable height therein so that the lock may be conveniently reached, a mortise 11, in which is fitted the lock casing 12, which, as shown, is rectangular in shape and has near its rear portion a transverse partition 13, which is provided with an opening 14, for the reception of one end of a split sleeve 15, and the operation of a portion of the locking bolt 16, which locking bolt is rectangular in cross section and has on its upper edge a series of projections 17, as well as a series of recesses 18, located between said projections. The front part of the bolt 16, is adapted to be reciprocated through an opening 19, in the front part of the casing 12, and the rear portion of the bolt 16, is reduced and adapted to operate in an opening 20, in the rear portion of the casing 12, as well as in an opening 21, formed in the door 10, so as to be in alinement with the opening 20, of the casing. 80 The mortise 11, in the door 10, has an opening 22, on each side of the door so that the indicating rings of the lock may be seen and reached from either side of the door. Each of these openings may be closed by means of a slide 23, which are held for vertical movement by means of guideways 24, secured to each side of the door. Surrounding the bolt 16, and the grooved sleeve or member 15, are a number of indicating rings each of which is designated as a whole by the reference numeral 25, and each of said rings consists of three parts, to-wit: a main disk 26, a supplemental disk 27, and a character bearing band 28, which surrounds said disks and has an inwardly extended flange 29, interposed between the outer portion of the disks 26, and 27, which may be secured together by means of small screws or rivets 30. Each of the main disks of each of the 100 rings 25, is provided on its inner face with a circular recess 31, and an opening 32, (see Fig. 5) for the reception and operation of the grooved member 15, and locking bolt 16, respectively. As shown in Fig. 5, each of the disks 26, of each of the rings 25, is provided with a recess 33, of sufficient size to permit of the passage of the projections 17, on the locking bolt 16, when said recesses are brought into alinement, and when said bolt 110 is reciprocated. Each of the disks 27, of each of the rings 25, is provided with an

opening 34, which is somewhat larger than the opening 32, in the disk 26, to which the disk 27, is secured on that surface of the former leaving the recess 31 thereon. Before the disks 26, and 27, are secured together, one of the character bearing bands 28, is placed around one of the disks so that its flange 29, will rest on the surface thereof, when the other disk can be placed on said flange and within the band 28, and the two disks secured together by means of screws 30, or rivets thus clamping the flange of the band 29, between said disks.

Each of the disks 26, and 27, is provided near its periphery with a series of small openings 35, and each of the flanges 29, is provided with one or more small openings 36, to register with the openings 35, and to receive a pin 37, used for securing the flange 29, against rotation between the said disks. This arrangement affords means for easily changing the combination, for it will be understood that each of the bands 28, of each of the indicating rings 25, has thereon a number of characters, such as the letters of the alphabet, the relative positions of which with respect to the recesses 33, in the disks 26, may be changed by removing the pin 37, from one set of openings in the disks 26, and 27, when by turning the band 28, so that its opening 36, will register with another set of the openings 35, of said disks and inserting the pin 37, therein, the characters on the band 28, will be fixed in another position with respect to the recesses 33, of its ring, from that which it formally occupied.

Extended transversely through the door and the upper portion of the lock casing 12, and suitably journaled in the door is a shaft, 38, which may have secured on each of its ends handles 39, or knobs, to be used for turning the same. This shaft has mounted thereon within the casing 12, a mutilated pinion 40, the teeth of which are adapted to engage teeth or projections 41, on the upper surface of the locking bolt 16, which teeth or projections are located near the middle thereof. Surrounding the reduced portion of the locking bolt 16, and located thereon between the partition 13, and the casing 12, is a coiled spring 42, which rests at one of its ends against the end of said casing and at its other end against a collar 43, secured to the reduced portion of the bolt 16, which collar will limit or restrict the forward movement of said bolt by reason of its contact with the partition 13, of the lock casing.

From the foregoing and by reference to the drawing, it will be readily understood and clearly seen, that as each side of the casing 12, is open, and that each side of the door 10, is provided with an opening 22, 65 which latter openings may be opened or ex-

posed and closed by means of the sliding doors 23, that when the lock is in position as shown in Figs. 1, to 3, inclusive of the drawing, the characters on the indicating rings 25, can be viewed from either side of the door. In assembling the parts the reduced or rear portion of the locking bolt 16, is first inserted inwardly of the casing 12, through the opening 19, therein, when the grooved sleeve 15, is placed on the inner portion of said bolt, which sleeve member may first have mounted thereon the indicating rings 25. The bolt 16, is then forced rearwardly so that its reduced portion will pass through the opening 14, in the partition 13, when the collar 43, and spring 42, may be placed on said reduced portion and the former fixed thereto at a point near the partition 13. The bolt or shaft 38, is then inserted through the openings in the door therefor and the pinion 40, mounted thereon, when it is apparent that the teeth of said pinion will engage the teeth 41, of the bolt 16, so that by turning the shaft 38, the locking bolt may be advanced or retracted. In order to permit of such movement of the locking bolt the indicating rings 25, composed of the disks 26, 27, and character carrying bands 28, must be arranged so that the recesses 33, in each of said rings will 95 align with one another, and also be brought into register with the teeth or projections 17, of the locking bolt. By arranging the bands 28, on the rings 25, so that a predetermined combination of the letters or characters thereon will be formed when the recesses 33, of the rings 25, are aligned and brought into register with the projections 17, on the locking bolt, it is apparent that said bolt may be projected or retracted, and 105 that it can be locked in either position by turning one or more of the rings 25, so that its recess will be thrown out of register with the said projections.

Having thus fully described my invention, what I claim as new and desire to secure by Letters-Patent is—

1. In a lock, the combination with a casing having its sides open and provided with openings between its upper and lower edges 115 for the reception and operation of a locking bolt and adapted to be mounted on a door, of a spring actuated locking bolt movably mounted in the openings of the casing therefor and having on one of its edges a series of spaced apart projections and a rack, a handled shaft extended transversely through the casing and journaled in the door, a pinion mounted on said shaft to engage the rack of the locking bolt, and a series of 120 rings surrounding the locking bolt within the casing and each ring consisting of a main disk, a supplemental disk, each having openings near its periphery and each provided with a central opening and one of 130

said disks with a radial recess, and a character bearing band surrounding the main disk and supplemental disk and provided with an inwardly extended flange interposed between said disks, said flange having an opening to register with the openings near the peripheries of said disks and adapted to receive a pin to secure said flange to the disks.

- 10 2. In a lock, the combination with a casing having its sides open and provided with openings between its upper and lower edges for the reception and operation of a locking bolt and adapted to be mounted on a door, 15 of a grooved sleeve located at one of its ends in one of said openings and extending longitudinally with respect to the casing, a spring actuated locking bolt movably mounted in said sleeve and said openings and having on its edge exposed through the groove of said sleeve a series of spaced apart projections and a rack, a handled shaft ex-

tended transversely through the casing and journaled in the door, a pinion mounted on said shaft to engage the rack of the locking bolt, a series of rings surrounding the locking bolt within the casing and each having a radial recess on its inner periphery to register with the projections on the locking bolt, each consisting of a main disk, a supplemental disk, each having openings near its periphery and each provided with a central opening and a character bearing band surrounding the main disk and supplemental disk and provided with an inwardly extended flange interposed between said disks, said flange having an opening to register with the openings near the peripheries of said disks and adapted to receive a pin to secure said flange to the disks.
